US00D954296S

(12) **United States Design Patent** (10) Patent No.: **US D954,296 S**
(45) Date of Patent: **** Jun. 7, 2022**

(54) **LABORATORY UTENSIL**

(71) Applicant: **Michael Thomas Hendrikx**, Landgraaf (NL)

(72) Inventor: **Michael Thomas Hendrikx**, Landgraaf (NL)

(**) Term: **15 Years**

(21) Appl. No.: **35/510,679**

(22) Filed: **Oct. 21, 2020**

(80) **Hague Agreement Data**

Int. Filing Date: **Oct. 21, 2020**

Int. Reg. No.: **DM/210956**

Int. Reg. Date: **Oct. 21, 2020**

Int. Reg. Pub. Date: **Nov. 6, 2020**

(51) LOC (13) Cl. **24-02**

(52) U.S. Cl.

USPC **D24/226**

(58) **Field of Classification Search**

USPC D24/216, 223, 224, 226; D9/756

CPC B01L 3/545; B01L 3/50851

See application file for complete search history.
